UNITED STATES PATENT OFFICE

FRED D. HOLDSWORTH, OF CLAREMONT, NEW HAMPSHIRE, ASSIGNOR TO SULLIVAN MACHINERY COMPANY, A CORPORATION OF MASSACHUSETTS

VALVE MECHANISM

Application filed December 31, 1923, Serial No. 683,605. Renewed October 29, 1929.

This invention relates to valve mechanism. It has for an object to provide an improved valve mechanism. A further object is to provide an improved plate valve mechanism which provides an unusually large inlet or discharge area. Another object is to provide improved plate valve mechanism in which the movement of the plate valve can be exceedingly small, but which will nevertheless 5 provide ample discharge area. Another object is to provide improved valve mechanism in which a plurality of plate valves may be used and operated in angularly disposed planes.

15 In the accompanying drawings I have shown for purposes of illustration one form which my invention may assume in practice. In these drawings,—

Fig. 1 is a plan view partially broken away 20 to show details of construction.

Fig. 2 is a vertical section on line 2—2 of Fig. 1.

Fig. 3 is a vertical section taken at right angles to Fig. 2 and on line 3—3 of Fig. 1.

25 Fig. 4 is a section taken on line 4—4 of Fig. 1.

Fig. 5 is a plan view of a plate valve used in the illustrative form of my invention.

Fig. 6 is a plan and side elevational view 30 of a valve spring which may be used in cooperation with the plate valve of Fig. 5.

In my improved valve mechanism I propose to use a plurality of plate valves disposed in different angular planes and in a common cage member, thus making a very compact device. To accomplish this I have shown for purposes of illustration one embodiment of my invention which comprises a base 1 having an annular flange 2. Disposed 35 in the base 1 are spaced longitudinal rib-like members 3; and valve seats 5 are formed on the upper surfaces of said members. The spacing of these members 3 results in upwardly extending passages 4 being formed 40 between or beside them. Transverse strengthening ribs 6 connect the various ribs 3 and flange 2. Ports 8 are formed between the members 3 so as to constitute continuations of the passages 4. The rib-like members 3 are hollow, with open tops, as is made

clear by Fig. 2. From Figs. 3 and 4 (noting particularly where these sections are taken) it will be understood that transversely disposed ports 7 project inwardly from each of the passages 4. Vertical valve seats 9 are 55 formed in the interior of the rib-like members 3 surrounding the ports 7 and extend, as shown in Figs. 1 and 4, between opposite inner points of the annular flange 2. The base 1 may be seated in a cylinder 12 by any suitable means (see Fig. 3), herein shown as a shoulder 13 formed in the periphery of the 60 annular flange 2.

The valves for covering the horizontal valve seats 5 comprise a single circular resilient plate 14 having parallel slots 15 leaving the strips 17 in between. Thus, these valve portions 17 when placed upon the upper surface of the base 1 will cover the various ports 8 while the openings 15 leave ample room for 65 discharge through the ports 7. The circular plate 14, and consequently the valves 17, is held in position by a transversely flexed spring 19 with its end portions slightly upwardly curved, which in turn is held in position by a cover 20 having a depending annular portion 21 adapted to seat adjacent the upper circular edge of the base 1 and which 70 is held in fixed relation thereto. Any suitable means may be used for holding the cover 20 and base 1 in fixed relation, such means herein shown as bolts 23 screw threaded into the base 1. It is not thought necessary to 75 describe the details of the clamping structure for holding the elements of the valve mechanism in assembled relation on the shoulder 13 of the cylinder, as it is of a well known type. The cover 20 is spaced from the surface 5 and has openings 24 therein for allowing flow of fluid from the ports 7 and 8. The 80 spring 19 is disposed within this space and held in coaxial relation with respect to the valve as by depending lugs 25, the outer surfaces of which are curved to fit the inner edge of the spring 19. The lugs 25 are also adapted to assist in guiding the valve 14, these lugs 85 projecting downwardly within the central opening 15 and seating upon the upper surface of the base 1.

Means for closing the ports 7 comprise re- 90

silient plate valves 26 and as shown in Fig. 1 a single transversely curved spring 27 is used to seat the pair of opposed plate valves 26 disposed over the opposed valve seats 9.

5 Thus, the central portion of the spring 26 engages the left hand valve while the outer ends of the same engage the right hand valve.

In the operation of my device it will of course be understood that my valve as shown 10 can be used either as an inlet or exhaust valve and when used in either manner fluid will flow through passages 4, and valves 17 and 26 will be opened in accordance with the amount of fluid flow through the passages 4.

15 It will be readily seen that the distance the valves 17 and 26 move will not be as great in order to allow a given amount of fluid flow as though only valves in a single plane were used and hence my improved construction 20 permits a very rapid action of the valve and a large flow of fluid therethrough without producing any hammering action or other disadvantages that are inherent with valves that move a great distance from their seats.

25 It will be seen that upon removal of the valve mechanism from the cylinder 12, the various plate valves can be maintained in their seated positions without the necessity of any special 30 precautions to prevent the various members from separating.

While I have in this application specifically described one form which my invention may assume in practice, it will be understood that this form of the same is shown for purposes of illustration and that the invention may be modified and embodied in other forms without departing from its spirit or the scope of the appended claims.

What I claim as new and desire to secure 40 by Letters Patent is:

1. A valve mechanism comprising a base member formed with plane valve seats traversed by ports communicating with a common source of fluid, a plurality of said seats 45 being disposed substantially in a common plane and another of said seats being disposed in a plane angularly disposed with respect to said common plane, the port which traverses the valve seat in the angularly disposed plane being so located that the projection on said common plane of every point in said port which traverses the valve seat in the angularly disposed plane lies within the confines of said plurality of seats, and plate 50 valves cooperating with said seats for controlling fluid flow through said ports.

2. A valve mechanism comprising a base member formed with plane valve seats traversed by ports communicating with a common 60 source of fluid, a plurality of said seats being disposed substantially in a common plane and another of said seats being disposed in a plane substantially perpendicular to said common plane, the port which traverses the valve seat in the substantially per-

pendicular plane being so located that the projection on said common plane of every point in said port which traverses the valve seat in said substantially perpendicular plane lies within the confines of said plurality of seats, and plate valves cooperating with said seats for controlling fluid flow through said ports.

3. A valve mechanism comprising a cage member having one short dimension and two relatively long dimensions, said cage member being provided with plane valve seats traversed by ports communicating with a common source of fluid, a plurality of said seats being disposed in planes angularly disposed with respect to the plane of said two relatively long dimensions and having their ports so disposed that a common plane parallel to the plane of said two relatively long dimensions will cut all of them, and another of said seats being disposed in a plane substantially parallel to the plane of said two relatively long dimensions, and plate valves cooperating with said seats for controlling fluid flow through said ports.

4. A valve mechanism comprising a base member formed with plane valve seats traversed by ports communicating with a common source of fluid, a pair of said seats and a third seat being disposed in substantially parallel planes with said pair of seats facing each other and said third seat disposed adjacent said pair of seats and facing away from said pair of seats, a fourth of said plane valve seats being disposed in a plane angularly disposed with respect to said parallel planes, the port traversing said last mentioned seat being disposed between the plane of the third seat and the nearer plane of the two in which lie said pair of seats, and plate valves cooperating with said four seats.

5. A valve mechanism comprising a base member formed with plane valve seats traversed by ports communicating with a common source of fluid, a pair of said seats and a third seat being disposed in substantially parallel planes with said pair of seats facing each other and said third seat disposed adjacent said pair of seats and facing away from said pair of seats, a fourth of said plane valve seats being disposed in a plane angularly disposed with respect to said parallel planes, the port traversing said last mentioned seat being disposed on the farther side of the farther plane from said third seat of the two in which lie said pair of seats, and plate valves cooperating with said four seats.

6. A valve mechanism comprising a base member formed with plane valve seats traversed by ports communicating with a common source of fluid, a pair of said seats being disposed in substantially parallel planes and facing each other, a third of said plane valve seats being disposed in a plane angularly disposed with respect to said parallel

planes, the port traversing said last mentioned seat being disposed outside the pair of planes in which lie said pair of seats, and plate valves cooperating with said three seats.

5 7. A valve mechanism comprising a base member formed with plane valve seats traversed by ports communicating with a common source of fluid, a pair of said seats being disposed in substantially parallel planes with 10 said pair of seats facing each other, a third of said seats being disposed in a plane angularly disposed with respect to said pair of planes, the port traversing said third seat being disposed outside the pair of planes in 15 which lie said pair of seats, a fourth of said seats being disposed in a plane angularly disposed with respect to said pair of planes, the port traversing said fourth seat being disposed on the opposite side of said pair of 20 planes from the port traversing said third seat, and plate valves cooperating with said four seats.

8. A valve mechanism comprising a base member provided with plane valve seats 25 traversed by ports communicating with a common source of fluid, a plurality of said seats being disposed substantially in a common plane and a plurality of said seats being disposed in planes angularly disposed with 30 respect to said common plane, the ports traversing the valve seats in the angularly disposed planes being so located that the projection on said common plane of every point in said ports which traverse the valve seats 35 in the angularly disposed planes lies within the confines of the seats disposed in said common plane, and plate valves cooperating with said seats for controlling fluid flow through said ports.

40 9. A valve mechanism comprising a base member provided with plane valve seats traversed by ports communicating with a common source of fluid, a plurality of said seats being disposed substantially in a common plane and a plurality of said seats being disposed in planes angularly disposed with 45 respect to said common plane, the ports traversing the valve seats in the angularly disposed planes being so located that the projection on said common plane of every point in said ports which traverse the valve seats in the angularly disposed planes lies within the confines of the seats disposed in said common plane, and plate valves cooperating with 50 said seats for controlling fluid flow through said ports, certain of said angularly disposed plate valves being movable in the same direction during opening.

60 10. A valve mechanism comprising a base member having plane valve seats traversed by ports, a plurality of said seats being disposed substantially in a common plane and a plurality of said seats being disposed in planes angularly disposed with respect to said 65 common plane, a pair of said last mentioned

seats facing each other, a single plate valve for covering said seats in said common plane, and separate valves cooperating with said seats in said angularly disposed planes, said valves cooperating with said pair of facing 70 seats moving toward each other during opening.

11. A valve mechanism comprising a base having a plurality of ported valve seats and a supplemental valve seat provided with a port, a single valve structure movable toward and from said plurality of valve seats for controlling flow of fluid through said ports, said valve structure having an opening therein acting as a passageway for fluid passing 75 through the port in said supplemental valve seat, and a valve element cooperating with said supplemental valve seat, the port of said supplemental valve seat being angularly disposed with respect to the direction of movement of said single valve structure. 80

12. A valve mechanism comprising a base member provided with plane valve seats traversed by ports, a single plate valve cooperating with and covering a plurality of said 90 seats, others of said plane valve seats being disposed in planes angularly disposed with respect to the plane of said plate valve, plate valves cooperating with said seats in the angularly disposed planes, each of said last mentioned valves cooperating with but a single seat, and means cooperating with said several valves for guiding each of the same to move bodily rectilinearly from its seat. 95

13. A valve mechanism comprising a cage member having plane valve seats traversed by ports communicating with a common source of fluid, a plurality of said seats being disposed in substantially parallel planes and being alined in pairs which face each other, 100 another of said plane valve seats being disposed in a plane angularly disposed with respect to said parallel planes, a valve member cooperating with said last mentioned valve seat, pairs of plate valves cooperating with 105 said pairs of alined valve seats, and valve seating spring means interposed between each pair of plate valves. 110

14. A valve mechanism comprising a base member formed with a plurality of inlet passages, said base member having plane valve seats traversed by ports communicating with said inlet passages, certain of said ports extending as continuations of said passages and in alinement therewith so that fluid flow 115 through said passages and alined ports takes place without change of direction, the valve seats traversed by said alined ports being arranged in the same or parallel planes, others of said valve seats facing each other and being arranged in planes disposed perpendicularly with respect to the plane of a seat traversed by an alined port. 120

15. A valve mechanism comprising a base member formed with plane valve seats 125

- traversed by ports, one of said ports being arranged to conduct fluid in the same direction as the initial direction of flow of said fluid into the valve mechanism, a plurality of said valve seats being disposed in planes angularly disposed with respect to the plane in which the valve seat traversed by said last mentioned port is disposed, and separate plate valves cooperating with said valve seats for controlling fluid flow through said ports, certain of the separate valves which cooperate with valve seats in the angularly disposed planes being simultaneously movable toward each other during opening while the plate valve cooperating with the valve seat traversed by the port arranged to conduct fluid in the same direction as the initial direction of flow of said fluid into the valve mechanism is movable in a different direction.
16. A valve mechanism comprising a base member having a plurality of passages extending in substantially parallel directions, and each opening into a port at its end and into lateral ports, and valves cooperating with said ports for controlling fluid flow through said passages.
17. In a valve mechanism, in combination, a base comprising a plurality of spaced ribs, the space between a pair of adjacent ribs having the outlet therefrom formed as a port, said ribs having fluid passages, each passage having a port, a valve cooperating with said first mentioned port to control flow of fluid through said space between a pair of adjacent ribs, and valve means cooperating with said last mentioned ports to control flow of fluid through said passages.
18. In combination in a valve mechanism, a base comprising a plurality of spaced substantially parallel ribs having fluid passages formed therein, the spaces between said ribs having the outlets therefrom formed as ports, each of said rib passages having a port, and separate valve means covering the ports of said spaces and the ports of said passages.
19. In combination in a valve mechanism, a base comprising a plurality of spaced substantially parallel straight ribs having fluid passages formed therein, the space between a pair of adjacent ribs having the outlet therefrom formed as a port, each of said rib passages having a port, a valve cooperating with said first mentioned port to control flow of fluid through said space between a pair of adjacent ribs, and valve means disposed within said passages for controlling flow of fluid through the ports thereof.
20. A valve mechanism comprising a base provided with valve seats traversed by ports, the directions of flow through a pair of said ports being opposed and the valve seats traversed by said pair of ports being opposed, a plurality of said valve seats being traversed by ports for conducting fluid in a direction at an angle to the directions of flow through said opposed valve seats, a single valve structure covering said plurality of valve seats traversed by ports for conducting fluid in an angular direction, plate valves covering the ports of said opposed seats, and a common means for holding to said opposed seats the plate valves cooperating therewith.
21. A valve mechanism comprising a base member having ports opening in substantially parallel directions, a generally annular flat plate valve for controlling fluid flow through said ports, additional ports formed in said member and opening in directions angularly disposed with respect to the directions of opening of said first mentioned ports, said additional ports and said first mentioned ports communicating with a common source of fluid, and plate valves for controlling fluid flow through said additional ports, said additional ports and the plate valves cooperating therewith being disposed within the radial limits of said general annular plate valve.
22. A valve mechanism comprising a member having a plurality of slots in one side thereof, a plurality of passages extending entirely through said member and on opposite sides of said slots, transverse ports connecting said slots and passages, plate valves adapted to control flow of fluid through said ports, and a plate valve seated on the surface of said member containing said slots for controlling flow of fluid through said passages.
23. A valve mechanism comprising a member having a plurality of slots in one side thereof, a plurality of passages extending entirely through said member and on opposite sides of said slots, transverse ports connecting said slots and passages, plate valves adapted to control flow of fluid from said ports, a plate valve seated on the surface of said member containing said slots for controlling flow of fluid through said passages, and a single spring means cooperating with said latter valve.
24. A valve mechanism comprising a cage member having one short dimension and two relatively long dimensions, said cage member being provided with plane ported valve seats disposed in planes angularly disposed with respect to the plane of said two relatively long dimensions and having their ports so disposed that a common plane parallel to the plane of said two relatively long dimensions will cut all of them, said cage member being formed with a bypass interposed between certain of said ports for passing additional fluid through said cage member, a valve for controlling said bypass, and valve members for controlling fluid flow through said ports.
25. A valve mechanism comprising a cage member having one short dimension and two relatively long dimensions, said cage member being provided with plane ported valve seats,

a plurality of said seats being disposed in planes perpendicular to the plane of said two relatively long dimensions and so aligned that a common plane parallel to the plane of said two relatively long dimensions will cut all of the ports thereof, a plurality of said seats being disposed in a plane or planes substantially parallel to said common plane cutting said ports, and valve members for controlling fluid flow through the ports of the valve seats disposed in the perpendicular and parallel planes, certain of the valve members co-operating with the valve seats in the perpendicular planes moving toward each other in opening.

In testimony whereof I affix my signature.
